UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

BOILER-TUBE CLEANER.

1,157,114.

Specification of Letters Patent. Patented Oct. 19, 1915.

Application filed April 23, 1915. Serial No. 23,364.

To all whom it may concern:

Be it known that I, FREDERICK W. LINAKER, a subject of the King of England, residing at Dubois, in the county of Clearfield 5 and State of Pennsylvania, have invented certain new and useful Improvements in Boiler-Tube Cleaners, of which the following is a specification.

This invention relates to certain new and 10 useful improvements in boiler tube cleaners and has relation particularly, to that type of cleaner in which one or more fluid distributing pipes are arranged transversely of the boiler tubes and have outlets through 15 which the cleansing fluid, such as steam, air or the like, is projected in the passes between the tubes for cleaning the latter of soot or other accumulations.

The present invention is an improvement 20 upon that type of cleaner shown, described and claimed in Letters Patent #1,041,140, granted October 5, 1912 to DeLos E. Hibner, wherein there is employed a stationary distributing pipe having nozzles provided 25 with a plurality of discharge ports arranged at different angles to the axis of the pipe; also upon Letters Patent #1,041,141 granted October 5, 1912 to James Moore, wherein the fluid distributing pipe em- 30 ployed is a rotary one, and also upon Letters Patent #1,041,080 granted October 15, 1912 to DeLos E. Hibner and myself wherein the rotatable distributing pipe that is employed is provided with nozzles that flex and are 35 caused to have their discharge ends main- tained on lines oblique to the axis of the distributing pipe by means of guide plates in which the nozzles move during the rotation of the distributing pipe.

40 The patented devices above referred to have gone into extensive use and been found generally satisfactory and efficient to accomplish the objects sought. With said prior patented devices however, some difficulty is encountered at times, due to boiler 45 conditions that exist, in installing the cleaner whereby there will be insured, during operation, a stream of cleaning fluid projected and maintained on the oblique lines or paths obtain- 50 ing between the rows of boiler tubes, and the present invention has for its primary and main object, the construction of a cleaner readily adaptable to any boiler con-

ditions that may exist to insure at all times during operation, the discharge of streams 55 of cleaning fluid on lines oblique to the axis of the distributing pipe between the rows of boiler tubes, and the maintaining of the correct oblique angle throughout the cleaning operation in order that all of the tubes 60 may be effectually cleansed, and all danger of the fluid, as steam, impinging on the tubes whereby the same could be cut or damaged is obviated.

The device is particularly adapted to boil- 65 ers of the Babcock & Wilcox type though not confined to use upon this specific type of boiler, as it may readily be adapted to other types, and it embodies in its construction and arrangement, one or more fluid dis- 70 tributing pipes that are rotatably mounted to revolve within stationary nozzles which have a multiple of discharge orifices ar- ranged so as to project the cleaning fluid be- 75 tween the boiler tubes in such manner that the lines of streams of fluid from one nozzle intersect and cross the lines of streams of fluid from another nozzle, which necessarily blow on intersecting planes.

A practical embodiment of the invention 80 as practiced is herein shown and will be de- scribed in detail, without however, confining myself to the specific construction shown or to the specific operating means shown, as these may be varied to suit conditions that 85 may exist, without departing from the spirit or scope of the invention as herein claimed.

In the drawings:—Figure 1 is a sectional side elevation of a boiler of the B. & W. type equipped with a tube cleaner in accordance 90 with this invention, it being understood that the feed pipe, branch pipes, and the dis- tributing pipe operating means shown in full lines are, in actual use, outside the boiler setting. Fig. 2 is a sectional front ele- 95 vation showing one of the distributing pipes and the manner in which the nozzles are spaced in relation to the boiler tubes. Fig. 3 is an enlarged view in side elevation of a practical and preferred form of operating 100 means for rotating the distributing pipe. Fig. 4 is a side elevation of the same, a part of the distributing pipe and the boiler setting being shown. Fig. 5 is a detail perspec- 105 tive view of a portion of the distributing pipe of a preferred form of construction.

Fig. 6 is a longitudinal sectional view of one of the nozzles and a part of the distributing pipe therein, the nozzle being shown in position on a boiler tube, the latter being in transverse section. Fig. 7 is a transverse vertical sectional view of one of the nozzles and distributing pipe taken on the line VII—VII of Fig. 6. Fig. 8 is a transverse vertical sectional view through the distributing pipe on line VIII—VIII of Fig. 6, showing the nozzle in end elevation. Fig. 9 is a detail perspective view of a part of a distributing pipe, showing a modified form of construction. Fig. 10 is a longitudinal sectional view similar to Fig. 6 showing the employment of the modified form of distributing pipe shown in Fig. 9, with a modified form of nozzle. Fig. 11 is a transverse vertical sectional view taken on the line XI—XI of Fig. 10 on a somewhat reduced scale. Fig. 12 is a transverse vertical sectional view of a further modified form of nozzle, capable of use with either form of distributing pipe, also on a somewhat reduced scale, and, Fig. 13 is a detail plan view of a further modified construction of cleaner for accomplishing the same result by a different disposition and arrangement of nozzles.

As the distributing pipe and its nozzles in the form shown in Figs. 1 and 2 is identical, the description of one in detail will suffice for all.

The distributing pipe is designated generally as 18 and may be of one piece, or made in as many sections as desired, and suitably connected together as at 19 (Fig. 2). The nozzles in the preferred form of construction now being described are designated generally by the numeral 20, and each nozzle consists of a barrel or sleeve in which the distributing pipe is rotated, each barrel or sleeve having a peripherally projecting face or faces arranged so as to project the steam down between the boiler tubes, and in such disposition or arrangement that the lines of streams of fluid from one nozzle intersect and cross the lines of streams of fluid from another nozzle. The barrel or sleeve which constitutes the nozzle body carries depending stirrup pieces 21 which straddle the boiler tubes 22 on which the nozzles rest, such stirrup pieces preventing the nozzles shifting longitudinally of the fluid distributing pipe, or from rotating, but allowing the nozzle to have, if necessary, a little vertical movement, so that the distributing pipe when revolved in the nozzles will not bind. Each nozzle face (there being two "faces" in the preferred form) is drilled to provide multiple orifices or ports 23, 23', these two series of ports extending in opposite directions, but both on lines oblique to the axis of the distributing pipe, as best seen in Fig. 6, so as to accurately and

definitely project the cleaning fluid into the obliquely extending spaces between the boiler tubes.

To co-operate with the nozzles, the distributing pipe 18 has a plurality of slots 24, 24' in opposite sides of the pipe, and so spaced that when the distributing pipe is revolved by a step-movement, the opening 24 will engage successively with the series of orifices or ports 23 and so project the fluid as required until such time as the opening 24', when the pipe has been revolved a predetermined arc, comes into successive coincidence with the series of orifices or ports 23' in order to project the fluid on planes intersecting the planes on which such fluid was projected through the orifices 23. It may be here noted, that only at one point do the openings 24, 24' at one time come in coincidence with the orifices or ports 23, 23', which point is when the distributing pipe 18 is turned to such position that the openings or ports 24, 24' are on the horizontal center line of the barrel or sleeve of the nozzle.

The revoluble distributing pipe 18 is introduced through the front wall A of the boiler setting through a sleeve 25. The inner end of this pipe is closed and is preferably anchored in the opposite wall A' of the boiler setting as shown at 26, Fig. 2. The outer end of this distributing pipe is screwed into a swivel-joint connection 27 which in turn is connected to the branch pipe 17. The swivel-joint 27 has a ratchet wheel 28 cast onto the body, and carries a lever-arm 29 held close to the ratchet wheel 28 by means of a collar 30. The lever-arm 29 carries a pawl 31 which engages with the teeth 32 of the ratchet-wheel 28 in order to revolve the distributing pipe 18.

Fixed to the front wall A of the boiler setting is a bracket 33 having outwardly-projecting arms 34 and 35 between which the lever-arm 29 extends, and these arms are so spaced that the movement permitted the lever-arm between them is such that the pawl 31 moves to revolve the distributing pipe 18 one tooth of the ratchet-wheel at a time. The teeth 32 of the ratchet-wheel are so arranged that as the distributing pipe and swivel-joint are revolved tooth by tooth, or as it were, step by step, the opening 24 or 24' in the distributing pipe comes successively into coincidence with the orifices or ports 23 or 23' as the case may be.

At the outer end of the lever-arm 29 is a knuckle-joint 36 held in position with bolt 37 passing through both the knuckle-joint and the lever-arm. Depending from this knuckle-joint is an operating handle or rod 38.

To operate the cleaner as above described, the supply valve 15' and shut-off valve 15* (Fig. 1) are opened, as is also the control valve 17' to the individual distributing pipe

or element 18 that is to be operated, and then the operator, by grasping the operating handle or rod 38 pulls down the lever-arm 29 until it strikes the projection or stop-arm 35 of the bracket 33. This has rotated the distributing pipe one tooth or step and the pipe is usually permitted to remain in this position for a few seconds, after which the operator raises or lifts up on the operating rod 38 so that the pawl 31 engages with the next tooth of the ratchet-wheel 28, whereupon the operator pulls down upon the rod 38 until the lever-arm again is arrested by the stop-arm 35. In this manner, step by step, the distributing pipe is completely revolved, so that, in turn, the steam or other fluid is projected first through all of the nozzle orifices or ports as 23 blowing in one direction, and then through all of the 20 nozzle orifices or ports as 23' blowing in the opposite direction.

With the form of construction where the distributing element 18 is arranged to revolve within the barrel or sleeve of the nozzle, it is preferable to provide the element 18 at the points where it turns in the barrels or sleeves somewhat enlarged in diameter from the body of the element as shown at 39, Fig. 6, for the purpose of providing sufficient body to the pipe to permit of trueing the same to neatly fit the barrels or sleeves, also to give more wearing body to the pipe at the points where it revolves in the barrels or sleeves, and to provide, if necessary, sufficient wall area to permit of the employment of a suitable packing as 40 to prevent the leakage of steam or other fluid at the ends of the barrels or sleeves.

The nozzles 20 instead of being provided 40 with multiple orifices or ports 23, 23' in the projecting face or faces thereof as in the construction just described, may be made with one continuous port or slot 23^a through the face or faces as shown in the nozzle 20^a 45 illustrated in Fig. 12.

With this construction, it will be observed that the arrangement provides for the projection of the fluid on oblique lines between the boiler tubes in a manner that the lines of 50 streams of fluid from one nozzle intersect and cross the lines of streams of fluid from another nozzle, which necessarily blow on intersecting planes. Now, this same result may be accomplished by using two cleaner elements or 55 distributing pipes, instead of one as shown in Fig. 1, for each pass of the boiler, and arranging a series of the multiple-ported or the slotted nozzles on one distributing pipe in each pass to project fluid on one plane, and arranging like nozzles on the other distributing pipe in each pass to project the 60 fluid down intersecting planes. Such an arrangement is illustrated in Fig. 13 wherein the nozzles that project the fluid in one 65 plane are designated 20^b, and the nozzles

that project the fluid down the other intersecting planes are designated 20^c. This construction however, materially adds to the cost of the installation without obtaining better or more efficient results.

Another construction by means of which the desired and afore-described projection of the cleansing fluid may be obtained is embodied in the showing in Figs. 9, 10, and 11. In this construction, the distributing pipe designated 18^a is adapted for step adjustment on its longitudinal axis instead of being rotatable, any suitable means diagrammatically shown at 18^x, being provided for effecting adjustment of the pipe. In this construction, the pipe is provided with a series of port openings or a slot so arranged that as the distributing pipe is moved by a step by step movement, the port openings or slot will in succession, become 80 coincident with the nozzle orifices. As illustrated, the pipe 18^a is shown as provided with two series of openings, the openings of one series being designated 40, 41, 42 and 43, and the openings of the other series designated 44, 45, 46 and 47. The nozzle 20^a has port openings the same as port openings 23 or 23' and designated 40', 41', 42', 43', 44', 45', 46' and 47', and it will be observed that by this construction, as the distributing pipe 18^a is moved longitudinally at one stage in the cleaning operation, 44 in the distributing pipe will coincide with 44' in the nozzle; at another stage 45 in the pipe will coincide with 45' in the nozzle; at the next stage 46 in the pipe will coincide with 46' in the nozzle; at another stage 47 and 43 in the pipe will coincide with 47' and 45' in the nozzle respectively; at another stage 42 in the pipe will coincide with 42' in the nozzle; at another stage 41 in the pipe will coincide with 41' in the nozzle, and at the final stage 40 in the pipe will coincide with 40' in the nozzle.

Obviously, the slotted nozzle of the form shown in Fig. 12 may be used with this construction of distributing pipe, the pipe being adjusted step by step to bring the orifices in the pipe successively coincident with the slot in the nozzle, the orifices in the pipe being so disposed as to project the fluid substantially on the same radius as do the port openings in the nozzle of port type.

It will be understood that with a construction in which the distributing pipe is moved longitudinally of its axis that provision is made to permit such longitudinal movement of the pipe, and that various means may be employed for adjusting the pipe, the specific means employed being immaterial, and not forming a part of the invention.

It will be plain from the foregoing description that with nozzles constructed and located as described, a cleaning fluid as

steam or air issuing from each and every nozzle orifice will be projected in a plane parallel to the plane between the tubes of the boiler so that the fluid at no time during the cleaning operation strikes or impinges upon the tubes whereby they might be cut or damaged.

What I claim as new is:—

1. In a tube cleaner, a fluid distributing pipe arranged transversely of the tubes of a boiler above the same and adapted for step by step adjustment on its axis, said pipe having outlet openings in its walls, and a plurality of stationary nozzles in which the pipe is adjustable, said nozzles having discharge ports with which the outlet openings in the pipe are brought into coincidence as the pipe is adjusted.

2. In a boiler tube cleaner, a fluid distributing pipe arranged transversely of the tubes of a boiler above the same and adapted for step by step adjustment on its axis, said pipe having outlet openings in its walls, a plurality of stationary discharge nozzles in which the pipe is adjustable, said nozzles having discharge ports with which the outlet openings in the pipe are brought into coincidence as the pipe is adjusted, and means for adjusting said pipe.

3. In a boiler tube cleaner, a fluid distributing pipe disposed transversely of the tubes of a boiler and having multiple outlets, stationary discharge nozzles in which said pipe is received and wherein it is adjustable, said nozzles having discharge ports with which the outlets in the pipe are brought into coincidence as the pipe is adjusted, a fluid supply communicating with the distributing pipe, and means for adjusting said pipe in said nozzles.

4. In a boiler tube cleaner, a fluid distributing pipe arranged transversely of the tubes of a boiler for adjustment on its axis and provided with multiple series of outlet openings, stationary nozzles in which said pipe is adjustable, said nozzles having discharge ports so arranged that in one position of the distributing pipe one series of outlet openings in the pipe are coincident with discharge ports of the nozzle and discharge the fluid toward one side of the boiler and in another position of the pipe, another series of the openings therein coincide with different nozzle ports to discharge fluid toward the opposite side of the boiler.

5. In a boiler tube cleaner, a fluid distributing pipe arranged transversely of the tubes of a boiler for adjustment on its axis and provided with outlet openings, and stationary nozzles in which the pipe is adjustable having discharge orifices and arranged throughout the pipe to project fluid from the pipe downwardly in oblique lines toward one side of the boiler in one position of the pipe and in another position of the pipe to

project the fluid downwardly in oblique lines toward the opposite side of the boiler.

6. In a boiler tube cleaner, a fluid distributing pipe arranged transversely of the tubes of a boiler for adjustment on its axis 70 and provided with outlet openings, stationary nozzles through which the pipe extends and in which it is adjustable, said nozzles having discharge ports disposed to project the fluid downwardly in oblique lines between the boiler tubes, the nozzles being so disposed that in one position of the pipe the fluid is projected downwardly toward one side of the boiler and in another position of the pipe the fluid is projected downwardly 80 toward the opposite side of the boiler, and means for adjusting said pipe on its axis.

7. In a boiler tube cleaner, a fluid distributing pipe arranged transversely of the tubes of a boiler for adjustment on its axis 85 and provided with outlet openings, stationary nozzles through which the pipe extends and in which it is adjustable, said nozzles provided with discharge ports and so disposed that when certain of the pipe outlets 90 are coincident with discharge ports in the nozzles the fluid is projected downwardly between the boiler tubes in oblique lines toward one side of the boiler and in another position of the pipe other outlet openings 95 thereof are coincident with nozzle ports and discharge the fluid downwardly between the boiler tubes in oblique lines toward the opposite side of the boiler.

8. In a tube cleaner for boilers, a distributing pipe arranged transversely across the tubes of a boiler above the same, said pipe adjustable on its axis and provided with fluid outlet openings, and stationary nozzles through which the pipe extends and in 105 which it is adjustable, said nozzles having discharge ports directed to project cleansing fluid obliquely to the distributing pipe, certain of the outlet ports in the pipe when coincident with nozzle discharge ports providing a fluid-projection in one direction and 110 other outlet ports in the pipe when coincident with nozzle discharge ports providing a fluid-projection in an opposite direction whereby the two lines of streams of fluid intersect and cross each other.

9. In a tube cleaner for boilers, a plurality of distributing pipes arranged transversely across the tubes of a boiler and revoluble on their axes, each pipe being provided with 120 two series of outlet openings, stationary nozzles through which the pipes extend and in which they are rotatable, each nozzle having discharge ports disposed to project cleaning fluid obliquely to the distributing pipe, said 125 nozzles when one of said series of pipe openings is coincident the nozzle discharge ports projecting the fluid toward one side of the boiler and when the other of said series of pipe outlet openings is coincident with nozzle 130

5 discharge ports projecting the fluid toward the opposite side of the boiler, the lines of streams in one fluid projection intersecting and crossing the lines of streams in the other fluid projection.

10. In a boiler tube cleaner, a fluid distributing pipe extending transversely of the tubes of a boiler and having outlet openings, and nozzles on the pipe each provided 10 with discharge ports disposed to project the fluid in oppositely-extending oblique paths between the boiler tubes, the lines of streams of fluid from certain discharge ports of the nozzles intersecting and crossing the lines of 15 streams of fluid from other discharge ports of the nozzles.

11. In a boiler tube cleaner, a fluid distributing pipe extending transversely of the tubes of a boiler and having outlet openings, 20 a fluid supply for said pipe, and nozzles on the pipe having discharge ports, certain of said nozzles at one time discharging the fluid in oblique lines in one direction and others of the nozzles at another time dis- 25 charging the fluid in oblique lines in an opposite direction.

12. In a cleaner for boilers, a fluid distributing pipe adjustably mounted across the tubes of a boiler and having outlet openings, 30 a fluid supply connected to said pipe, and stationary nozzles having discharge ports directed to project cleaning fluid along oblique lines between the boiler tubes when the distributing pipe is adjusted to bring the 35 outlet openings thereof and the discharge ports of the nozzles into coincidence.

13. In a tube cleaner, an adjustable fluid distributing pipe, and a plurality of nozzles through which the pipe extends and in 40 which it is axially adjustable, the pipe having outlet openings within the nozzles and the nozzles having discharge ports adapted to project the fluid among the tubes to be cleaned when the pipe is adjusted to bring 45 said outlet openings of the pipe and discharge ports of the nozzles into registry, the outlet openings in the pipe being normally out of registry with the discharge ports in the nozzles.

50 14. In a tube cleaner, a rotatable fluid distributing pipe, a plurality of stationary nozzles through which the pipe extends and in which it is revoluble, the pipe having outlet openings in its walls within the nozzle and 55 the nozzles having discharge ports adapted to project cleaning fluid from the pipe among the tubes to be cleaned when the pipe

is rotated to bring the outlet openings thereof and the discharge ports of the nozzles into registry, the outlet openings in the pipe 60 being normally out of registry with the discharge ports in the nozzles.

15. In a tube cleaner, an adjustably-mounted fluid distributing pipe, and a plurality of spaced stationary nozzles through which 65 said pipe extends, the pipe having outlet ports within the nozzles and the nozzles having discharge ports adapted to project cleaning fluid from the pipe among the tubes to be cleansed when the pipe is adjusted to 70 bring the outlet openings thereof into registry with the discharge ports of the nozzles, means for imparting a step by step adjustment to said pipe to bring said outlet openings into and out of registration with said 75 discharge ports, and a fluid supply connected to the pipe.

16. In a tube cleaner, a fluid distributing-member and a nozzle-member through which the distributing member extends, one of said 80 members being axially-adjustable with relation to the other member, each member having discharge ports, the discharge ports of one member being brought into registry with the discharge ports of the other member 85 by movement of the adjustable member on its axis.

17. In a tube cleaner, a fluid distributing-member and a nozzle-member, one of said members being stationary and the other being adjustable on its axis to vary its position 90 with relation to the stationary member, each member having discharge ports, the discharge ports of one member being brought into registry with the discharge ports of the other member 95 by movement of the adjustable member on its axis.

18. In a tube cleaner, a fluid distributing-member and a nozzle-member, one of said members being stationary and the other being adjustable to vary its position with relation to the stationary member, each member having discharge ports, the discharge ports of one member being brought into registry with the discharge ports of the 100 other member by movement of the adjustable member.

In testimony whereof I affix my signature in presence of two witnesses.

FREDERICK W. LINAKER.
